2 SHEETS-SHEET 2.

UNITED STATES PATENT OFFICE.

ALBERT D. CAYWOOD, OF CHICAGO, ILLINOIS.

DOOR-CONTROLLING MEANS.

SPECIFICATION forming part of Letters Patent No. 733,624, dated July 14, 1903.

Application filed May 9, 1902. Serial No. 106,649. (No model.)

To all whom it may concern:

Be it known that I, ALBERT D. CAYWOOD, a citizen of the United States, residing at Chicago, in the county of Cook and State of Illinois, have invented a new and useful Improvement in Door-Controlling Means, of which the following is a specification.

My invention relates particularly to means for automatically controlling the closing of fire-doors, being directed especially to means for controlling the closing of fire-doors for hatchways, elevator-shafts, and the like.

My primary object is to provide simple and efficient means for automatically controlling the closing of fire-doors.

My invention is illustrated in its preferred embodiment in the accompanying drawings, in which—

Figure 1 represents a broken sectional view 20 of a building, showing a series of hatchways with fire-doors equipped with my improved automatic controlling means; Fig. 2, an enlarged broken sectional view similar to Fig. 1 and showing the upper story of the building; 25 Fig. 3, an enlarged broken sectional view illustrating a fuse-link employed, and Fig. 4 a detached perspective view of one of the main weights employed for releasing the locking means of the door-retainers.

30 The preferred construction is as follows:

A A' A² represent a series of floors having a series of openings or hatchways provided with doors B B' B²; C C' C²; a series of door-retainers; D, a series of blocks or locking devices for locking the retainers in the retaining position; E, a chain passing over a pulley E', connected with the ceiling E² of the uppermost story of the building and having chain connections E³ with the blocks D; F F' 40 F², a series of normally-restrained potentially-operative similar devices for moving the chain E and releasing the blocks D; G G' G², a series of wires passing over pulleys a and equipped with auxiliary weights a' and serving to release the main weights of the chain-actuating devices F F' F², and G³ a series of fuse-links interposed in the wires.

As indicated, the devices F F' F² are similarly constructed. Each comprises a vertically-disposed box or casing b, a normally elevated main weight b', provided with a vertical channel b², receiving the chain E, and a

horizontal groove affording a shoulder b³, a weight-retainer b⁴, pivotally secured at b⁵ to a plate b⁶ and having a short arm b⁷ projecting through a slot b⁸ in the casing b and engaging the shoulder b³ of the weight b', a spring-held lever or catch b⁹, pivotally secured at b¹⁰ to a lug of the plate b⁶ and having a hook b¹¹ engaging a stud b¹², with which the 60 long end of the lever b⁴ is provided, and a chain b¹³, connecting the free end of the lever b⁹ with the adjacent wire of the G series. The chain E is provided with a series of stops d, located a short distance below the weights b', 65 as more clearly appears from Fig. 2. The chain E is also provided with a weight d', which serves to counterbalance the stops d. One wall of each casing b is extended upwardly to afford a support for a plate f, having a recess f' for receiving one end of a block D.

Each of the door-retainers is supported on pivot f², carried by bracket-arms f³, projecting from the plate f. As shown, the retainer is 75 in the form of a lever, pivoted at its center and provided at its upper end with a recess f⁴ for receiving one end of a block D. The blocks D are connected loosely with the chain E by means of the chains E³, the connection 80 of each block with its chain being near an end of the block.

The pulleys a are located beneath the ceilings of the several stories, and the wires passing over them connect with the links G³ in 85 the manner shown. It will be understood that the wires are suitably supported and may be provided with any number of fuse-links. Usually each wire is carried around the hatchway and provided with several fuse-links, and wires connected therewith and provided with fuse-links lead away from the hatchway. One of the links G³ is shown in Fig. 3, from which it will be observed that each link comprises a member g, provided 90 with a cavity g', having conical walls, a member g², provided with a projection g³, having conical walls and fitting into the cavity g', and a rivet g⁴, of fusible material, connecting the members together. It will readily be seen 95 that when the rivet is fused the members will be permitted to separate under the tension which is ordinarily placed upon them.

In the construction shown the doors are

vertically disposed in the open position, being hinged at their lower ends. A series of springs *h* tend to force the doors to the closed position and cause sufficient pressure on the retainers to hold the blocks *D* in position.

The operation will be readily understood from the foregoing detailed description. When one of the rivets *g* is fused by heat, the auxiliary or tripping weight held by the wire with which the fuse-link is connected is permitted to drop and trip the corresponding lever *b*, thereby permitting the weight *b*' to turn the lever *b*' and fall upon the stop *d*. The weight *b*' is sufficiently large to move the chain *E* and disengage the blocks *D* from the door-retainers, whereupon the door-retainers are permitted to turn freely and the doors are permitted to fall.

It readily will be seen that the wires and fuse-links are under but comparatively slight tension, while the chain *E* is under no tension. Nevertheless, the apparatus is delicately responsive and thoroughly efficient in operation. In case of fire on any floor of the building the apparatus located on that floor will serve to actuate the chain *E* and cause all the doors of the hatchways to be closed.

A common use for apparatus of this character is in connection with elevator-shafts of warehouses, and the hatchways shown in Fig. 1 may be understood as representing the openings in the floors for an elevator-shaft.

Changes in minor details of construction within the spirit of my invention may be made. Hence no undue limitation is to be understood from the foregoing detailed description. For instance, the door-retainers and locking means therefor, the chain connected with said locking means, a weight for actuating said chain, and retaining means for said weight may be used in connection with any suitable means for permitting the movement of said last-named retainer to allow the weight to fall. Thus the weight-retainers may be controlled by electromagnets in fuse-controlled circuits.

What I claim as new, and desire to secure by Letters Patent, is—

1. In means of the character described, the combination of a pivoted door-retaining lever,

a block engaging the base end of said lever and serving to hold the other end in engagement with the door, a chain, connected with said block, and passing over a suitable support, a main weight for actuating said chain, 55 tripping mechanism normally supporting said weight, and an auxiliary weight suspended by fusible connections and serving to move said tripping mechanism.

2. In means of the character described, the combination of a series of door-retainers normally held in the retaining position, a chain, serving to release said retainers and passing over a suitable support, a series of main weights for moving said chain, a series of supports for said weights supplied with tripping mechanism and a series of independent auxiliary weights suspended by independent fusible connections and serving to move said tripping mechanism, substantially as and for 70 the purpose set forth.

3. In means of the character described, the combination of a series of door-retainers normally held in the retaining position, a chain, for releasing said retainers and passing over 75 a suitable support, a series of main weights, supports for said weights supplied with tripping mechanism, a series of weight-stops on said chain, a series of independent auxiliary weights for moving said tripping mechanism, 80 and supporting means for said auxiliary weights with independent fuse connections, substantially as described.

4. In means of the character described, the combination of a door-retainer normally held 85 in the retaining position, a chain, for releasing said retainer passing over a suitable support, a main weight for actuating said chain, a guide for said main weight, a weight-retainer pivoted on said guide and having a 90 downwardly-extending arm, a transverse catch pivoted on said guide and engaging the arm of said retainer, and a fuse-supported auxiliary weight serving to move said catch, for the purpose set forth.

ALBERT D. CAYWOOD.

In presence of—

A. C. KITTLESON,
ALBERT D. BACCI.
